UNITED STATES PATENT OFFICE

168,037

FOOD MIXER BODY

Clarence Karstadt, Glen Ellyn, Ill., assignor to
 Birtman Electric Company, a corporation of
 Illinois

Continuation of abandoned design application
 Serial No. 15,372, June 1, 1951, which is a con-
 tinuation of abandoned design application Se-
 rial No. 10,240, May 27, 1950. This application
 December 29, 1951, Serial No. 17,867

Term of patent 14 years

(Cl. D44—1)

To all whom it may concern:

Be it known that I, Clarence Karstadt, a citizen of the United States, residing at Glen Ellyn, in the county of Du Page and State of Illinois, have invented a new, original, and ornamental Design for a Food Mixer Body, of which the following is a specification, reference being had to the accompanying drawings, forming a part thereof, in which:

Fig. 1 is a side elevation of a food mixer body showing my new design; Fig. 2 is a rear end elevation of said food mixer body; Fig. 3 is a front end elevation of said food mixer body; Fig. 4 is a plan view of said food mixer body; Fig. 5 is a bottom view of said food mixer body; and Figs. 6, 7 and 8 are sections showing the outline of the food mixer body substantially along lines 6—6, 7—7 and 8—8, respectively, of Fig. 1.

This application is a continuation of my appli-

cation Serial No. D. 15,372, filed June 1, 1951, which in turn was a continuation of my application Serial No. D. 10,240, filed May 27, 1950; both of which are now abandoned.

I claim:

The ornamental design for a food mixer body, as shown and described.

CLARENCE KARSTADT.
